KNIFE SHARPENER

Alexis E. Meade and Margaret L. Meade,
Lakewood, Ohio

Application June 5, 1940, Serial No. 338,866

13 Claims. (Cl. 51—214)

This invention relates to knife sharpeners and one object of the invention is to provide a small, light and compact portable device for this purpose. Another object is to provide means for removably supporting the abrasive members of the sharpener together with retaining means for the same, which are readily releasable when the abrasive members require replacement. A further object is to provide a portable knife sharpener in which the abrasive members are supported in oppositely oblique positions upon slideable carriers having relatively broad bases to insure easy sliding movement. And it is also an object of the invention to provide carriers for the abrasive members designed to protect the guideways on which they move to prevent the accumulation of abrasive dust thereon. Other objects and advantages will appear as the description proceeds. The invention consists in certain features and elements of construction in combination as herein shown and described and as indicated by the claims.

In the drawings:

Figure 1 is a side elevation of a portable knife sharpener embodying this invention.

Figure 2 is a top plan view of the same.

Figure 3 is the bottom plan view.

Figure 4 is a vertical sectional view taken as indicated at line 4—4 on Figure 2, but on a larger scale.

Figure 5 is a transverse section taken as indicated at line 5—5 on Figure 4.

Figure 6 is a fragmentary vertical section showing a modified form of abrasive retainer.

Figure 7 is a fragmentary perspective view showing another form of abrasive retainer.

Fig. 8 is a fragmentary detail section showing another form of abrasive retainer.

Figure 9 is a fragmentary detail section showing a further modification of abrasive retainer.

Figure 10 is a perspective view showing one of the carriers removed from the frame, but with the abrasive members mounted thereon.

Figure 11 is a perspective view of the other carrier with its abrasive member.

Figure 12 is a perspective view of a stop member.

Figure 13 is a partial back view of one of the carriers.

Figure 14 is a side elevation of a modified form of sharpener having certain parts adapted for folding when out of use.

Figure 15 is a side elevation showing the parts folded in collapsed position.

The sharpener which is the subject of this

invention is of the type in which a plurality of abrasive members are disposed in oppositely oblique planes to form a V-shaped space into which the cutting edge of a knife is received so that as the blade is reciprocated the abrasive members act on both sides of the blade simultaneously to sharpen its cutting edge. In addition the abrasive members are mounted on carriers which are slideable so as to permit the abrasives to move apart as the blade is pressed down between them, thus bringing into action the full length of each abrasive surface, while suitable spring means holds said surfaces yieldingly in contact with the knife blade which is being sharpened. As shown in Figure 1 the sharpener includes a case or frame 1 which is approximately rectangular in outline and consists essentially of side walls and end walls. In the form illustrated in Figures 1 to 5 the case includes top or cover portions 2 at both ends, but its middle portion is left upwardly open to provide clearance for movement of the abrasive carriers and to afford ready access to the abrasives themselves. The end walls 3, 3 of the case support longitudinal guide rods 4, 4 on which the abrasive carriers are slidably mounted. The carrier 5 is shown supporting two stones or abrasive members 6, 6 while the carrier 1 is provided with a single stone or abrasive member 8 extending between the stones 6, 6. The working faces of the stones 6, 6 extend in a plane which is oblique to the vertical, and the working face of the stone 8 extends in a plane oppositely oblique as seen in Figures 1 and 4, thus providing a V-shaped opening into which the edge of a knife blade such as that shown at A in Figure 1 may be inserted for sharpening.

The carrier 5 which supports the stones 6, 6 includes a base portion 9 having a bearing flange 10 at one end and bearing lugs 11, 11 at the other end with aligned bores in said flange and lugs to fit the guide rods 4, 4 of the frame 1. The carrier includes upstanding portions which provide inclined channels to receive the abrasive stones 6, 6 between their side flanges 13 and these channel portions are shown connected by a web 14 and reenforced by a bracing rib 15. The other carrier 1 includes a single channel between whose side flanges 18 the stone 8 is fitted and this channel is supported by a rib 19 upstanding from the base 20 which includes a longitudinally extending portion 21 connecting transverse flanges 22 and 23 which are bored to fit on the rods 4, 4 of the frame. When the parts are assembled the portion 21 of the base

20 extends between the lugs 11, 11 of the base 9 and the flange 23 rides on the guide rods 4, 4 under the base 9 so that the two bases are thus interlapped to conserve space and to operate in a case of minimum length. Figure 4 shows the carriers at one limit of their range reciprocative movement on the guides 4, 4 with the stones 6 and 8 closely approaching each other and leaving only a small V-shaped opening between the planes of their upper ends to receive the knife blade. Figure 1 shows the stones and their carriers separated by the maximum amount so as to permit the knife blade to pass between the lower ends of the stones.

The frame 1 includes or is provided with up-standing guides 24 at both sides, each having a vertical guide slot 25 to receive the knife blade and maintain it in substantially vertical position as it is forced downwardly between the abrasive stones 6 and 8. Near their lower ends the guide slots are constricted as seen at 26 to a width somewhat less than the normal thickness of a knife blade so that although the sharpened cutting edge may pass through these constricted portions of the slots 26 the downward movement of the blade A will be arrested by the constriction. Below this point each of the slots has an enlarged clearance opening 27 so as to avoid contact with the cutting edge of the knife blade. The angle of the constriction 26 in the slot 25 is not such as to cause the blade to be gripped in the slot or to seriously interfere with further movement of the blade between the stones 6 and 8, but it serves to definitely limit the vertical range of movement of the blade between the stones and to protect the edge which is being sharpened. At all times the stones are yieldingly urged toward each other by means of a single tension spring 28 anchored at one end in the flange 10 of the carrier 5 and engaged at the other end with a hook 29 in the flange 22 of the carrier 7. This single tension member 28 presses the stones 6 and 8 against opposite faces of the knife blade with equal pressure; but with the blades inserted between them the stones and their carriers are free to move in either direction as a unit on the guide rods 4, 4 except that their position is controlled by the engagement of the knife blade in the guide slots 25 of the upstanding guides 24.

To insure that the V-shaped opening between the abrasive stones shall register initially with the slots 25 the frame 1 includes fixed stops 30 which extend obliquely upward to engage substantial portions of the working faces of the stones 6, 6; and a bridge piece 31 is secured in slots 32 of the side walls of the frame so as to support an upwardly extending stop lug 33 to engage the working face of the stone 8. Thus the stones are stopped at definite points in their respective movements toward the slot 25 so as to leave limited portions of their working faces at the upper ends exposed for initial engagement with the knife blade and since the stops 30 and 33 engage the working faces of the stones this condition will be maintained as the stones wear away because the wear will be followed up by the tension of the spring 28 always urging the working faces of the stones against the stops.

As shown in the drawings, each of the stones is of rectangular cross-section, but has oppositely inclined or beveled ends, and the channels between flanges 13 and 18 of the carriers terminate at their lower ends in the acutely angu-

lar pockets to fit the beveled ends of the stones. At the upper end each stone is secured by a retainer 34 which, as shown in Figure 4, may be made of spring metal formed with a hook-shaped 5 lower end to fit around a lug 35 on the carrier, and with a bent upper end which overhangs the beveled end of the stone. The side flanges 13 and 18 of the channels, the pockets at their lower ends, and the retainers at the upper ends 10 overlap only a portion of the depth of each stone, thus leaving a generous portion of each of the abrasive members 6 and 8 exposed for work and wear. When the exposed portions have been almost worn away the spring retainers 35 may be readily disengaged from the upper ends of the stones. The back of each channel is cut away at the upper end between the side flanges, as seen at 5a in Figure 13, to make it easy to grasp the upper ends of the stones for 20 slidably withdrawing them and inserting new ones.

Figure 6 shows a modified form of retainer 36 consisting of an acutely angular metallic pocket loosely carried on a threaded stud 37 projecting from the back of the carrier. The pocket 36 is clamped in position by means of a thumb nut 38 and when the stone is to be replaced it is only necessary to loosen or remove the nut 38 and disengage the pocket 36 from the upper end of 25 the stone.

Figure 7 shows another form of retainer consisting of a wire loop or band 39 having its lower end engaged in a notched lug of the carrier while its upper end bears against the upper bevelled 35 end of the stone. In retaining position the upper end of the loop 39 is wedged against the end surface of the stone so that to release the stone it is only necessary to swing the loop backward out of wedging position.

40 In Figure 8 the retainer 41 is an acutely bent clip engaging the bevelled end of the stone and formed with a lug 42 through which a clamping screw 43 extends into a threaded boss 44 on the back of the supporting channel. Figure 9 shows 45 a variation of this arrangement in which the angular clip 45 has a lug 46 engaging the threads of a tension rod 47, while a threaded lug 48 engages an oppositely threaded portion of the rod 47. The upper end of the rod may be squared 50 at 49 so that its rotation in one direction clamps retainer 45 against the end of the stone while opposite rotation releases the retainer.

It will be noted that in all forms of retaining elements herein described, since the carriers 5 and 7 and the upper ends of the stones 6 and 8 are exposed through the upwardly open portion 55 of the case 1, the adjustment of the retainers and replacement of the stones is rendered extremely simple and does not require disassembling any of the mechanism.

As a safety feature each of the upstanding members 24 in which the guide slots 25 are located is provided with upwardly projecting guard flanges 50 which extend from the bottom of the 60 case substantially to the upper ends of the slots 25, although if desired the flanges may be tapered upwardly as shown in Figure 5. To operate the sharpener the user will grasp the sides of the case between the thumb and fingers of one hand, holding the knife in the other hand and pressing it firmly downward through the slots 25, while at the same time reciprocating the blade to subject it to the abrasive action of the stones. The guard flanges 50 insure that the thumb and fingers will not be placed over or

in line with the guide slots 25 so as to be injured by the cutting edge of the knife as it descends into the slots. And to permit the stones to operate as close as possible to the hilt or handle of the blade indicated at B in Figure 2, the guard flanges 50 are spaced at a substantial distance from the slots 25. The symmetrical design of the casing 1 renders it likely that it may be grasped and held by either end; accordingly guard flanges 50 are provided at both sides of the slots 25; and since the interlapping arrangement of the stones precludes having them closely adjacent the side walls of the frame at both sides of each of the slots 25, it may be desirable for the user to reverse the sharpener end for end in the process of sharpening a blade so as to insure equal abrasive action on both sides of the cutting edge. This is an additional reason for the symmetrical design of the case and for the provision of guard flanges 50 at both sides of the guide slots 25.

In the course of operation as the working faces of the stones 6 and 8 wear away, the dust of abrasive material thus produced will be carried downward and might tend to cause rapid wear of the guide rods 4, 4 and bores of the carriers which ride thereon if it should lodge on the guide rods. Therefore, the upper faces of the carriers adjacent the guide rods 4 are preferably made convex with downwardly sloping edges so as to shed the dust and allow it to fall past the rods onto the table or other support, the case 1 preferably being made open at the bottom. Thus the edges of the base portion 9 are shown sloping downwardly at 9a and the edges of the portion 21 of carrier 7 are similarly bevelled at 21a. Directly below the V-shaped opening which is formed between the working faces of the stones or rods 4 are completely covered by upwardly convex or V-shaped portions 11a of the lugs 11, thus minimizing the chance that any of the abrasive dust will lodge on the guide rods themselves.

For convenience of assembling, the rods 4 may be understood as of tubular formation with their end portions threaded and with retaining screws 54 inserted through counter-sunk openings in the end walls 3 of the case 1. However, any other conventional arrangement may be employed for securing the rods removably in the frame. In order that the cover portions 22 may enclose as much of the mechanism as possible the central opening of the case is made with elongated slots or notches 52 as seen in Figure 2 for accommodating the bracing ribs 15 and 19 of the carriers in their reciprocation.

Since the stops 30 and 33 extend parallel to the working faces of the stones 6 and 8, and both engage substantial portions of the length of said stones or abrasive members, they will maintain the proper relation of the stones with respect to the guide slots 25 as the working faces of the stones wear away with use. This wear will be fairly well distributed over the length of each stone, because, ordinarily, the knife blade will be carried past the lower ends of the abrasives to the position at which it is arrested by the guide slot constrictions at 26, but the extreme upper ends of the stones will not be subject to much wear because they are separated, as shown in Figure 4, at the beginning of the working stroke. However, since both ends of each stone are beveled at the same angle, it is a very simple matter to release the spring clip 34 and reverse the stone, end for end, when it

has become partly worn. This will not only insure a proper distribution of wear but will continue to provide a suitable entering opening between the upper ends of the stones as the wear on their working faces allows their carriers to be drawn closer together by the spring 28. And since the retainers 34 and the upper ends of the stones are readily accessible without, in any way, disturbing the other parts of the sharpener, this reversal can be accomplished in a few seconds and as frequently as the user finds it desirable.

Figures 13 and 14 illustrate a modified design adapting the sharpener to be folded into a package of minimum dimensions so as to be readily packed and carried as a part of the kit of a woodsman or hunter. For this purpose the case or frame 60 may consist of a simple peripheral wall entirely open at the top. The base portions of the carrier and their guide rods may be similar to those already described but the upstanding portions 65 and 67 of the carriers are shown hingedly connected at 66 and 68, respectively, to their bases and braced in upstanding position by struts 69 which are pivotally secured in lugs 70 of the carrier bases and which merely bear disengageably against lugs 71 of the parts 65 and 67. For packing the device the struts 69 are swung down to the position shown in Figure 14 and the hinged carrier members 65 and 67 are also swung to horizontal position reducing the height of the device by about one-half. The guide slots 75 are formed in upstanding arms 74 of a detachable yoke in which the parts 74 are connected by a cross-bar member 73 normally extending under the frame 60. Rounded bosses 76 engage holes 77 in the sides of the frame, but for packing the device this yoke may be sprung sufficiently to release the bosses from the holes 77, permitting removal of the yoke and its replacement in horizontal position over one end of the frame with its bosses 76 engaging holes 78 as seen in Figure 14. The entire device may then be fitted into a suitable rectangular case, not shown.

While there is shown and described herein certain specific structure embodying the invention, it will be manifest to those skilled in the art that various modifications and re-arrangements of the parts may be made without departing from the spirit and scope of the invention, and that the same is not limited to the particular form herein shown and described, except in so far as indicated by the appended claims.

We claim:

1. In a knife sharpener, a frame providing a fixed guide slot for a knife blade, a pair of carriers, abrasive members supported thereon with their working faces in intersecting planes, and a guideway on the frame on which said carriers are mounted for reciprocation transversely of the guide slot and toward and from each other, each carrier having a base portion extended in the direction of said guideway and lapping past the base of the other carrier, with bearing portions at the ends of said base portions engaging the guideway, the bearing portions at one end of one carrier engaging the guideway between the bearing portions of the other carrier on said guideway.
2. In a knife sharpener, a frame, parallel guide rods extending longitudinally in the frame, a pair of carriers mounted for reciprocation on the guide rods, abrasive members supported on the carriers with their working faces in intersecting planes, one carrier having base portions extend-

ing longitudinally over the guide rods with bearing portions at their ends slidable on the rods, said base portions having laterally sloping upper surfaces, the other carrier having a base portion which extends longitudinally between the vertical planes of the rods with laterally projecting bearing portions at its ends slidably engaging said rods, and said base portion of said other carrier having laterally sloping upper surfaces whereby both carriers will shed abrasive dust falling on said bases, the frame being open at the bottom for the escape of said dust.

3. In a knife sharpener, a frame, parallel guide rods extending longitudinally in the frame, a pair of carriers mounted for reciprocation on said rods, one carrier having base portions extending longitudinally over the guide rods with bearing portions at their ends engaging the rods, the other carrier having a base portion which extends longitudinally between the bases of the first mentioned carrier and which has laterally projecting bearing portions engaging the rods, and abrasive members supported on said carriers with their working faces extending obliquely upward and disposed respectively above said base portions and intermediate the bearing portions of the carriers on which they are supported.

4. In a knife sharpener, a frame, parallel guide rods extending longitudinally in the frame, a pair of carriers mounted for reciprocation on said rods, one carrier having base portions extending longitudinally over the guide rods with bearing portions at their ends engaging the rods, the other carrier having a base portion which extends longitudinally between the bases of the first mentioned carrier and which has laterally projecting bearing portions engaging the rods, and abrasive members supported on said carriers with their working faces extending obliquely upward and disposed respectively above said base portions, the upper surfaces of the base portions adjacent the lower ends of the abrasive members sloping laterally downward to protect the guide rods from abrasive dust.

5. In a knife sharpener which includes a plurality of abrasive members disposed with their working faces in planes which intersect at an acute angle, and guiding means controlling the relative movement of said members and maintaining the angular relation between their working faces as they are moved apart by the introduction of a knife blade between them, means providing a guide slot for such blade, said slot narrowing to a constricted portion at which the width of the slot is less than the thickness of such blade back of its cutting edge, and with a wider portion beyond the constriction affording clearance for the cutting edge when it passes through the constriction.

6. In a knife sharpener which includes a plurality of abrasive members disposed with their working faces in planes which intersect at an acute angle, and guiding means controlling the relative movement of said members and maintaining the angular relation between their working faces as they are moved apart by the introduction of a knife blade between them, means providing a guide slot for such blade, said slot narrowing to a constricted portion at which the width of the slot is less than the thickness of such blade back of its cutting edge, said constriction being located below the level of the lower ends of the working faces of the abrasive members.

7. In a knife sharpener, a frame, a pair of car-

riers, abrasive members supported thereon with their working faces in intersecting planes, and a guideway on the frame on which said carriers are mounted for reciprocation toward and from each other, each carrier having a base portion extended in the direction of said guideway and lapping past the base of the other carrier, with bearing portions at the ends of said base portions engaging the guideway, together with wear compensating stops on the frame extending upwardly for contact with the working faces of the abrasive members over substantial portions of their length.

8. In a knife sharpener, a frame providing a fixed vertical guide slot and a horizontal guideway extending transversely thereof in opposite directions therefrom, a pair of carriers both mounted for sliding movement on said guideway, and abrasive means on said carriers disposed respectively with their working faces in oppositely oblique relation to the guide slot and in planes which intersect at the plane of the slot, together with a single spring yieldingly connecting said carriers to each other independently of the frame, urging them toward each other and thereby applying the abrasive means with equal pressure to opposite sides of a knife blade inserted in the slot.

9. In the combination defined in claim 8, each of said securing elements comprising a clip of spring metal having a hook-shaped lower end engageable with a lug at the back of the channel and an angularly bent upper end fitting over the inclined upper end of the abrasive member.

10. In the combination defined in claim 8, said securing means including an angularly bent clip fitting over the inclined upper end of the abrasive member, and threaded means engaging said clip with a lug projecting from the back of the channel whereby the clip may be clamped endwise against the abrasive member.

11. In a knife sharpener, an upwardly open oblong frame, a pair of carriers, longitudinal guideways on the frame on which said carriers are mounted for reciprocation toward and from each other, each carrier having a base portion engaged with the guideways and an upstanding portion hinged thereto, abrasive members supported on the upstanding portions of the carriers with their working faces in intersecting planes, and bracing means on the bases supporting the upstanding portions but disengageable therefrom to permit said portions to be folded down toward the frame in compact arrangement.

12. In a knife sharpener, an upwardly open oblong frame, a pair of carriers, a longitudinal guideway on the frame on which said carriers are mounted for reciprocation toward and from each other, each carrier having a base portion engaged with the guideway and an upstanding portion hinged thereto, abrasive members supported on the upstanding portions of the carriers with their working faces in intersecting planes, upstanding guide means at each side of the frame providing a guide slot perpendicular to the guideway at a plane substantially bisecting the angle between the planes of said working faces, and bracing means on the bases supporting the upstanding portions but disengageable therefrom to permit said portions to be folded down toward the frame in compact arrangement, said upstanding slotted guide means being adjustable for disposing their slots horizontally to reduce the height of the sharpener for packing.

13. In a knife sharpener, a frame, a pair of

carriers, a guideway on the frame on which said carriers are mounted for reciprocation toward and from each other, yielding means urging the carriers toward each other, and abrasive members supported on the carriers with their working faces disposed in intersecting planes for contact with opposite faces of a blade to be sharpened by reciprocation in its own plane between said abrasive members and under downward pressure tending to urge them apart in opposition to said yielding means, each abrasive member having parallel side walls and end walls oppositely and obtusely inclined to the working faces of the

member, the carriers having channels with side walls between which said members are fitted and with end walls at the lower ends inclined to overlap portions of the inclined ends of the abrasive members, together with disengageable securing means overhanging portions of the inclined upper ends of said members whereby the abrasives are held captive in the channels with their working faces and adjacent portions of their side walls exposed.

ALEXIS E. MEADE.
MARGARET L. MEADE.
